[57] **CLAIM**

The ornamental design for a cabinet, as shown and described

DESCRIPTION

FIG. 1 is a front perspective view of a cabinet showing my design; and

FIG. 2 is a rear perspective view thereof;

FIG. 3 is a front perspective view of a modified form of the cabinet shown in FIG. 1; and

FIG. 4 is a rear perspective view thereof.

The sides of the cabinet now shown in FIGS. 1 and 3 are mirror images of the respective sides shown.
